UNITED STATES PATENT OFFICE.

CHRISTIAN A. KRUM, OF BURBANK, CALIFORNIA.

BOX-FASTENING.

1,095,119.

Specification of Letters Patent. Patented Apr. 28, 1914.

Application filed June 19, 1912. Serial No. 704,589.

To all whom it may concern:

Be it known that I, CHRISTIAN A. KRUM, a citizen of Norway, residing at Burbank, in the county of Los Angeles, State of California, have invented a new and useful Improvement in Box-Fastenings, of which the following is a specification.

This invention relates to fastening devices provided in the construction of boxes, and its principal object is to provide a fastening means for boxes built of light weight material to which a cover may be secured without the use of nails, after the boxes have been filled.

It is also an object to provide a box fastener with a larger supporting surface on its edge than the thickness of the material of which the box is composed.

It is also an object to provide a cover fastener that will be in a continuous strip and reinforce the edges of the box.

A further object is to provide a combined cover fastener and holder adapted to secure a lining in the box.

In the drawings accompanying this specification and forming a part of the application, Figure 1 is a perspective view of a box with a portion of the cover shown in place and secured by my device; Fig. 2 is a perspective sectional view showing the fastening means in cross section; Fig. 3 is a perspective view of a portion of the fastening device viewed from the inner side; Fig. 4 is a detailed plan view showing the notch cut in the material of the fastener, one of the parts being bent upon itself, shown in dotted lines, to form a corner.

Referring more particularly to the drawings, 5 is a box of the usual form commonly used to pack citrus or other fruit, with the sides 6-6 forming a rectangular structure on which is placed my fastener 7 formed of a plurality of engaging surfaces or planes, 8, 9 and 10. The material of which the fastening is composed, is preferably a thin sheet of metal of a light but stiff material as sheet steel. Formed upon the engaging plane 8 by pressing in a punch press, or by other means are the teeth or prongs 11, triangular in form and preferably projecting in a plane at right angles to that from which they are punched. Previous to forming the first bend in the metallic band, the clamp members or fasteners 12 are cut from the metal and are allowed to remain in the same plane, the balance of the band being bent to

form a plane or shelf 9 at right angles to the securing plane 8 and adapted to engage the edge and form a shelf or reinforcement for the same.

To further strengthen the box and insure the locking of the teeth in the material of the box and form a holder for a lining, the metal is further bent upon itself to form a plane 10 which bears upon the inner surface and clamps the whole securely to the box.

To provide the most economical form, the fastener is preferably built of a continuous strip and at the proper intervals, to register with the corners of the box, notches or recesses 13 are cut in the two planes 9 and 10, preferably triangular in section so that the plane 8 carrying the fastening members may be bent upon itself at the point 14, the corner 15 of the notch being folded under plane 9 when the bend is made, thus forming a stiff and strong corner.

As will be readily seen, as the clamp or box securing lug 12 is cut previous to the bend it projects in the same plane as the side of the box and the cover 16 is readily dropped into position and the lugs bent over along the line 17, the metal having been punched in such a form that this line 17 occupies the position of the least resistance in the formation of the lug. It will also be readily seen that if a sufficient ductile material is used, the lugs may be readily turned over by manual means without jar-ring the articles contained in the box, the contained articles frequently being very delicate, and the lugs may be turned back again to release the cover without material injury.

What I claim is:

1. A box fastener, comprising a flat metallic band bent upon itself to form a channeled structure having a gripping edge and a plurality of oppositely disposed securing means formed integral with said band, a portion of said band forming a supporting shelf intermediate of said gripping edge and the securing means, and integral clamping members to secure a cover to said shelf.

2. A metallic band formed of a strip bent upon itself to form a triangular channel having three surface planes, clamp means struck from the intermediate plane and securing means formed integral therewith on the exterior of said planes, the other two planes to one side of said exterior plane be-

ing cut transversely to form a triangular notch on the intermediate plane, to adapt the exterior plane to be bent at the apex of said notch and the portion of said cut intermediate plane overlapping when so bent to brace the corner of said strip when embracing a box corner.

In witness that I claim the foregoing I have hereunto subscribed my name this 11th day of June, 1912.

CHRISTIAN A. KRUM.
